UNITED STATES PATENT OFFICE.

MINNIAFFEE J. JARDEE AND ROBERT J. COWELL, OF ST. JOSEPH, MISSOURI.

OIL BURNER.

Application filed October 8, 1921. Serial No. 506,227.

To all whom it may concern:

Be it known that we, MINNIAFFEE J. JARDEE and ROBERT J. COWELL, citizens of the United States, residing at St. Joseph, in the 5 county of Buchanan and State of Missouri, have invented certain new and useful Improvements in Oil Burners, of which the following is a specification.

Our invention relates to new and useful 10 improvements in oil burners and one object is to provide a burner in which refined petroleum can be economically employed as a fuel.

Another object is to so form the burner 15 that the combustible mixture shall be evenly distributed throughout said burner so that when ignited it will heat the burner uniformly throughout without superheating certain portions thereof.

20 A further object is to provide means for preventing the unconsumed portion of the gas in the generator when the same is shut off to extinguish the flame, from giving off offensive odors which ordinarily arise from 25 such unconsumed gas when the burner is again lighted.

A further object is to provide a burner generator with a dust collector in which the fine particles of carbon and other foreign 30 matter formed in said generator are caught before they can reach and choke the discharge port.

Other objects will hereinafter appear, and in order that the invention may be fully understood, reference will now be had to the 35 accompanying drawing, in which:

Fig. 1 is a plan view of the burner with a portion of its generator broken away.

Fig. 2 is a side elevation.

40 Fig. 3 is an enlarged vertical section through the rear portion of the burner and its mixing chamber.

Fig. 4 is an enlarged horizontal section of a portion of the burner generator taken 45 on line IV-IV of Fig. 2.

Referring now in detail to the various parts, 2 designates the body of the burner which is substantially rectangular in contour. The upper wall 4 of the burner is 50 highest at its center as indicated at 6 from which it slopes towards its front and rear ends 8 and 10, respectively, the slope being greater towards the front end in order to correspondingly reduce the inside area of 55 the burner.

The upper and side walls of the burner

have saw cuts or slits 12 for the escape of the combustible mixture which is ignited just at the exterior of the burner. All of the walls of the burner are, preferably, cast 60 integral and the rear wall is equipped with a supplemental wall 14 which is removably secured in place by suitable means such as machine screws 15. The wall 14 is provided with an integral mixing chamber 16, 65 the inlet end 18 of which is spaced from the rear wall 15, so that air may be readily drawn therein by the suction of the gas as it is expelled from the discharge nozzle 20 of the generator 22. The lower end of the mixing 70 chamber 16 is slightly contracted and communicates with an inlet 21 and the rear wall of the burner 2 into which the combustible mixture is discharged.

The upper wall 4 of the burner body 2 75 has a trough 26 extending longitudinally thereof to receive noncombustible absorbent material such as asbestos wool, which on being saturated with alcohol or other inflammable liquid, will ignite and produce a 80 flame sufficient to initially start the generation into gas of the liquid fuel in the generator 22.

The generator 22 is supported just above the upper wall 4 of the burner 2 by a saddle 85 30, formed integral with the upper front portion of the burner, and the supplemental wall 14, which has an opening 32 to receive the forward end of said generator 22.

The generator 22 consists of a tube 34 and a goose-neck 36 threaded or otherwise secured to the rear end of said tube 34. The goose-neck 36 is provided with a rearward extension 38 equipped at its rear end with the discharge nozzle 20, which is supported 90 in alignment with the inlet 18 of the mixing chamber 16. The goose-neck 36 is also provided with a lateral extension 40 in which a dust collector 42 is threaded and adapted 95 to intercept foreign matter which would otherwise choke the discharge nozzle 20. As disclosed by Fig. 4, said dust collector 42 projects inwardly beyond the bore of the extension 38 and has small perforations 44 100 which permit the generated gas to pass freely to the discharge nozzle 20 but intercept carbon and other foreign matter which is carried back into a chamber 46, where it accumulates until the dust collector 42 is removed and cleaned. As a further precautionary measure to prevent the nozzle 20 105 from becoming choked, I provide the exten-

sions 38 with a fine mesh screen 50, to intercept and collect any particles that might find their way through the perforations 44 in the dust collector 42.

5 The front end of the generator tube 4 is connected to a needle valve 52 which communicates with a supply pipe 54 leading from a suitable source of oil, not shown. The shell 56 of the needle valve 52 is formed integral with the shell of a drain valve 58 through which the unconsumed gas in the generator 22 may be drained off, the tube 34 sloping downwardly at its forward end for that purpose.

15 In order to start the burner the material in the trough 26 is ignited to heat the generator 22, after which the needle valve 52 is opened to allow the oil to pass into the heated generator where it is formed into a gas which escapes through the discharge nozzle 22 with sufficient force to pass through the mixing chamber 16 and drawing air therewith enter the body 2 of the burner, through the slits 12 of which it escapes and is ignited. The flame thus produced heats the burner 2 and the generator 22, so that the process of generating the oil into gas will continue until the supply of oil is cut off. The combustible mixture expands as it enters the heated burner body 2, the greatest expansion occurring approximately within the central portion of the burner, and to a less degree at its rear end, and a lesser degree at its forward end, the peculiar shape 35 of the top wall 4 compensating for these differences in pressure, with the result that the combustible mixture issues at an even pressure, or approximately so, from all of the slits 12, and on becoming ignited as 40 above stated, uniformly heats the burner instead of superheating certain portions thereof and causing irregular expansion and contraction which would eventually result in the destruction of the body portion 2.

45 From the foregoing description it will be readily understood that we have provided a burner and a generator embodying the advantages above set forth, and while we have shown and described the preferred 50 construction, combination and arrangement

of parts, we reserve the right to make such changes as properly fall within the spirit and scope of the appended claims.

Having thus described our invention, what we claim and desire to secure by Letters Patent, is:

1. In a device of the character described, a burner body tapering towards its ends and having openings therein for the escape of a combustible mixture, a rear wall removably secured to said burner body, a curved mixing chamber supported by said rear wall, the upper intake end of said mixing chamber being spaced from the rear wall while the lower or discharge end of said mixing chamber terminates flush with said rear wall and communicates with the rear portion of the body to discharge the combustible mixture into said body, a generator provided with a goose neck and extending longitudinally of the burner body and arranged to discharge into the intake of the mixing chamber, and a trough extending longitudinally of the burner body and beneath said generator for the purpose described. 65

2. In a device of the character described, a generator consisting of a tube, a goose-neck fixed to said tube and provided with rearward and lateral extensions, a discharge nozzle fitted to the rearward extension, and a tubular dust collector closed at its outer end and having its open inner end projecting into the lateral extension. 70

3. In a device of the character described, a generator consisting of a tube, a goose-neck fixed to said tube and provided with rearward and lateral extensions, a discharge nozzle fitted to the rearward extension, a screen within the rearward extension, and a perforated dust collector closed at its outer end and removably fitted at its open inner end into the lateral extension. 75 80 85

In testimony whereof we affix our signatures, in the presence of two witnesses.

MINNIAFFEE J. JARDEE,
ROBERT J. COWELL.
